UNITED STATES PATENT OFFICE

108,989

DESIGN FOR A VEHICLE SEAT OR SIMILAR ARTICLE

Frank E. Van Hoesen, Chicago, Ill.

Application December 22, 1937, Serial No. 73,804

Term of patent 7 years

To all whom it may concern:

Be it known that I, Frank E. Van Hoesen, a citizen of the United States residing in Chicago, in the county of Cook and State of Illinois, have invented a new, original, and ornamental Design for a Vehicle Seat or Similar Article, of which the following is a specification, reference being had to the accompanying drawing, forming part thereof.

Fig. 1 is a perspective view of a vehicle seat embodying my new design.

Fig. 2 is a side elevation of this new vehicle

seat, the elevation of the opposite side to that shown in Fig. 2 being substantially identical in appearance with that shown in Fig. 2.

Fig. 3 is a front elevation of this new vehicle seat.

Fig. 4 is a plan view of this new vehicle seat.

Fig. 5 is a rear elevation of this new vehicle seat.

I claim:

The ornamental design for a vehicle seat or similar article, as shown and described.

FRANK E. VAN HOESEN.
